BY *Edwin H. Brown* THEIR ATTY.

UNITED STATES PATENT OFFICE.

THOMAS GORDON AND WILLIAM R. SWIFT, OF NEW YORK, N. Y.,
ASSIGNORS TO THE GORDON-MITCHELL GAS LAMP COMPANY,
OF SAME PLACE.

LAMP HAVING A REGENERATIVE BURNER.

SPECIFICATION forming part of Letters Patent No. 554,866, dated February 18, 1896.

Application filed April 3, 1891. Serial No. 387,500. (No model.)

To all whom it may concern:

Be it known that we, THOMAS GORDON and WILLIAM R. SWIFT, of New York, in the county and State of New York, have invented 5 a certain new and useful Improvement in Lamps Having Regenerative Burners, of which the following is a specification.

We will describe a lamp embodying our improvement and then point out the novel features in the claims.

In the accompanying drawing the figure represents a lamp having a regenerative burner embodying our improvement.

A' designates a gas-supply pipe descending 15 from any suitable source of gas, and B' designates a gas-chamber consisting of a top b, a cylindric part b' and a diaphragm b² formed integral with said cylindric part. The top may be united by a screw-thread or otherwise 20 with the cylindric part. A number of tubes b³ are arranged in a circular row and fitted to the diaphragm b². Their upper ends extend into the gas-chamber and their lower ends extend to a considerable distance below the 25 same. The lower ends pass through holes in a ring b⁴, which serves to sustain them transversely. Outside the cylindric part b' of the gas-chamber a deflector consisting, as here shown, of a cylindric sheet-metal shell b⁶, is 30 fitted. This deflector extends almost as low as the gas-tubes b³. The upper part of the gas-chamber communicates with and is attached to the gas-supply pipe. From the lower diaphragm or bottom of the gas-chamber a post b¹⁰ extends. To the lower extremity of this post a part H' is attached by means of a screw-thread, a set-screw H² or otherwise. The upper portion of the part H' has a number of radial passages for the entrance of air 40 and at its outer circumference an upwardly-inclined flange g¹⁰, from whose inner edge extends upwardly an inclined flange g¹¹. Above the flange g¹⁰ a similarly-inclined ring g¹² is arranged. This has an upwardly-inclined flange g¹³ at its inner edge. The ring g¹² and its flange g¹³ are shown as being made of perforated sheet metal and supported by arms g¹⁴ extending to a cylinder g¹⁵ which rests upon the part H'. The ring g¹² and its flange 45 g¹³ may, however, be made of imperforate metal. Above the ring g¹² is a ring D', which is supported by arms extending from a cylin-

der d', surrounding the post b¹⁰ and resting upon the part H'. This ring D' has the lower portion of its outer surface inclined similarly 55 to the ring g¹² and the lower portion of its inner surface inclined like the flange g¹³ of this ring. The upper part of the ring D' is provided with a seat d² for a combustion-chamber of globular form E' and it is also 60 constructed to form a seat for an air-distributer C'.

The combustion-chamber is surmounted by a cap J consisting of a ring sustained by arms extending from a ring fitting the gas-supply 65 pipe A'.

It will be seen that in our improvement the air for the lamp is taken in at the base of the combustion-chamber and that there is at the base of the lamp an atmospheric injector. 70

What we claim as our invention, and desire to secure by Letters Patent, is—

1. The combination with a regenerative burner, of a combustion-chamber, a gas-chamber, having a diaphragm, a post connected to and extending downwardly from said diaphragm, an air-distributer projecting into the combustion-chamber, an air-injector communicating with the distributer and located at the base of the combustion-chamber, 75 comprising the part H' provided with radial air-passages and circumferential upwardly-inclined flanges g¹⁰ and g¹¹, the ring g¹², above the part H' having upwardly and downwardly inclined flanges, and the ring D' located above 80 ring g¹² having inclined faces, said part H' and rings being connected to and supported by the post extending from the diaphragm, substantially as described.

2. An air-injector for a lamp comprising the 90 part H' provided with radial air-passages and circumferential upwardly-inclined flanges g¹⁰ and g¹¹, the ring g¹², above the part H', having upwardly and downwardly inclined flanges, and the ring D', located above the ring g¹², having 95 inclined faces, substantially as specified.

In testimony whereof we have signed our names to this specification in the presence of two subscribing witnesses.

THOMAS GORDON.
WILLIAM R. SWIFT.
